AUTOMATIC-MANUAL WINDOW OPERATOR

Herbert G. Lehmann, Bridgeport, Conn., assignor
to Casco Products Corporation, Bridgeport,
Conn., a corporation of Connecticut

Application December 29, 1950, Serial No. 203,399

14 Claims. (Cl. 268—124)

1

This invention relates to manual- and power-operated windows, such as are found in automobiles and the like.

The invention is concerned with improvements in the power-operated window described and claimed in the copending application of Joseph H. Cone, Serial No. 195,624, filed November 14, 1950, entitled "Power-Operated Window."

An object of the invention is to provide an improved manual- and power-operated window mechanism wherein opening and closing of the window may be effected either manually or by power at the will of the operator, without resorting to presetting or change-over operations or the like to shift from one type of operation to the other.

Another object of the invention is to provide an improved manual- and power-operated window mechanism for opening and closing the window either manually or by power, wherein the window is automatically locked in adjusted position and automatically released prior to its being opened or closed manually or by power.

A further object of the invention is to provide an improved window mechanism according to the foregoing, wherein the manually operable member of the mechanism is stationary when the window is being actuated by power.

Still another object of the invention is to provide an improved manual- and power-operated window mechanism for both opening and closing the window, which is so organized and arranged that manual actuation of the window may be effected without resorting to any disconnect operation between the power unit and the window whatsoever, thus simplifying the mechanism involved.

A still further object of the invention is to provide an improved window actuating mechanism as set forth in the immediately preceding paragraph, wherein the window is automatically locked in adjusted position at all times that it is not being operated.

Yet another object of the invention is to provide an improved manual- and power-operated mechanism according to all the foregoing, which is simple and compact in construction, economical to fabricate and reliable in operation at all times.

A feature of the invention resides in the provision of window operating mechanism, wherein hand power may be utilized to supplement the power operator should the window be difficult to shift initially, as when it becomes frozen to the guide strips, or frames, etc.

2

Other features and advantages will hereinafter appear.

In the accompanying drawings:

Figure 1 is an elevational view of the improved manual- and power-operated window mechanism of this invention, part of the manual operating mechanism not being shown.

Fig. 2 is a detail partly in elevation and partly in section, looking in the direction of the arrows 2—2 in Fig. 1, the parts of the mechanism being in the positions they assume when the window is being power-operated.

Fig. 3 is a fragmentary vertical section taken on line 3—3 of Fig. 2.

Fig. 4 is a view like Fig. 2, but with the parts in the positions they assume when the window is being operated manually.

Fig. 5 is a horizontal section, enlarged, taken on line 5—5 of Fig. 1.

Fig. 6 is a view partly in elevation and partly in vertical section, the vertical section being taken on line 6—6 of Fig. 5.

Fig. 7 is a circuit diagram of the electrical portion of the window mechanism.

Fig. 8 is a detail showing a modified form of locking means for use with the mechanism of Fig. 1.

Fig. 9 is a view partly in section and partly in elevation, the section being taken on line 9—9 of Fig. 8.

Referring to Fig. 1, a windowpane 10 is shown, mounted on a bottom frame member 11 of channel or similar shape, the frame member being secured to the pane 10 in any suitable manner.

Where the windowpane 10 is to constitute one of the windows of an automobile, it may be carried in side channels or guides (not shown) as is well understood.

For actuating the windowpane 10 the frame member 11 is provided with brackets 12 having slots 13 accommodating pins 14 carried by the ends of levers 15. At other ends, the levers 15 are connected by pivot pins 16 with uprights 17 and 17a, the levers crossing each other when the windowpane 10 is in fully lowered position as shown, and being pivotally connected together by a pivot pin 18.

The upright 17 is fixedly mounted on a base 19 carried by a bracket 20, and the upright 17a is pivotally mounted on the base 19.

In Fig. 1, the raised position of the windowpane 10 is shown by a broken outline 21, and positions of the levers 15 are shown by broken outlines 22 and 23, corresponding to both the raised position of the windowpane 10 and also the

half-raised or half-lowered position of the windowpane respectively.

For the purpose of operating the windowpane 10 by power, an electric motor 24 is provided, carried by a bracket 25 which is secured to the upright 17. The motor 24 is connected through an impositive drive mechanism with one of the levers 15 to actuate the same for lowering and raising the window. This impositive drive mechanism, as shown in Figs. 5 and 6, comprises a link 26 pivotally joined to one lever 15 by a pivot pin 27, the link being carried in a rigid tubular sheath or tube 28 secured to the upper casing part 29 of the motor 24. Within the casing part 29 are divergent shafts 30 carrying worm wheels 31 driven by a worm 32 mounted on the shaft 33 of the motor 24. The shafts 30 carry friction wheels or pulleys 34 which frictionally engage a flexible driving element or strip 35 connected to the lower end of the driving link 26. The flexible strip 35 passes between the pulleys 34 and is under continual pressure therefrom, and when in retracted position as shown in Fig. 6 extends within a tubular sheath 36 which may have a curved or circular shape as shown in Fig. 1.

Reference may be had to the copending application of Joseph H. Cone above referred to, for further details on the friction drive between the motor 24 and the windowpane 10.

By the present invention, in combination with the powered friction drive described above there is provided a novel means to enable the window 10 to be easily and conveniently manually actuated when so desired, together with means for automatically locking the window in any adjusted position.

Referring to Figs. 2, 3 and 4, the frame structure which carries the windowpane 10 is shown as having spaced parallel walls 37 and 38 which rotatably carry a shaft 39 having at one end an operating handle 40. The shaft 39 is round and has a portion 41 of larger diameter. On the small-diameter portion of the shaft 39 a square section 42 is rotatably carried, the latter having a pair of locking gears 43 and 44 normally held axially apart by a helical compression spring 45. The gears 43 and 44 are keyed to each other by virtue of the square section 42 which carries them. The gear 44 normally meshes with a gear segment 46 which is rigidly fastened to one of the levers 15, and said gear has a hub 44a provided with a round bore for receiving the circular portion 41 of the shaft 39.

Adjacent the gear 43 a bell crank 47 is mounted, having an arm 48 adapted to extend between the teeth of the gear 43 and lock the latter against turning. The bell crank 47 has a second arm 49 connected with a plunger 50 of an electric solenoid 51 whereby the arm 48 may be shifted out of engagement with the teeth of the gear 43 as shown in Fig. 2.

It will be understood that whenever the bell crank is engaging the teeth of the gear 43 the gear segment 46 will be locked, as will the windowpane 10, and whenever the bell crank is out of engagement with the gear 43 the gear segment 46 and the windowpane 10 will be free for movement.

Energization of the solenoid 51 is automatically effected prior to energization of the motor 24, whereby automatic unlocking of the windowpane 10 will be had whenever the motor is energized to operate the windowpane.

In accomplishing this I employ a switch means and circuit as illustrated in Fig. 7. As shown,

the motor 24 has an armature 52 connected by a wire 53 with a battery 54, which for example may be the battery of the car on which the window mechanism is installed. A wire 55 leads from the armature 52 to a center tap 56 of a field coil 57. One end of the field coil 57 is connected by a wire 58 with a contact 59 of a switch 60, and the other end is connected by a wire 61 with an opposite switch contact 62. The solenoid 51 is connected by a wire 63 to the wire 53, and by a wire 64 to another set of opposite contacts 65 and 66 of the switch 60.

The switch 60 may be of the telephone, lever type, having a blade 67 connected by a wire 68 with the battery 54. When the blade 67 is moved from centralized position in one direction or the other it will first engage and energize one or the other of the contacts 65, 66 and will thereafter cause said one contact to engage and energize the corresponding one of the contacts 59, 62. Thus, for operation of the switch 60 in either one direction or the other the solenoid 51 will first be energized, and thereafter the motor 54 will be energized. Movement of the switch blade 67 in one direction will cause forward rotation of the motor 24, and movement in the other direction will cause reverse rotation of the motor.

In accordance with this invention means are provided whereby the windowpane 10 may be raised or lowered manually, either in conjunction with the motor 24 or independently of the motor, by turning the handle 40, such means however enabling the handle 40 to remain stationary whenever the window is being power-operated.

Accordingly, referring to Fig. 2, I provide a pinion 69 on the round portion 41 of the shaft 39, said pinion being axially slidable on said shaft portion and being engageable with the gear segment 46. The pinion 69 has a hub 70 provided with a V-slot 71 accommodating a pin 72 carried by the shaft portion 41. Engageable with the pinion 69 at all times is a gear 73 rotatably carried on a stud 74, said gear having its turning retarded by friction means comprising a compression spring 75 and abutment washer 76. The purpose of the gear 73 is to provide a drag at all times on the pinion 69. Accordingly, whenever the handle 40 is turned, the pin 72 on the shaft 39 will ride along one or the other of the sloping portions of the V-slot 71, thereby camming the pinion 69 to the left. The drag produced on the pinion 69 by the gear 73 is sufficient to insure such camming and axial movement of the pinion. In so moving, the pinion will displace the locking gear 44 from engagement with the gear segment 46, shifting the locking gear to the left and compressing the spring 45, all as shown in Fig. 4. In place of the gear 44 meshing with the gear segment 46, the pinion 69 will now mesh with the gear segment. This will automatically unlock the gear segment and at the same time simultaneously provide for movement of the gear segment and of the windowpane when the handle 40 is turned. Accordingly the handle 40 may be operated to either raise or lower the window 10 whenever desired, since the window is always first automatically unlocked by disengagement of the gear 44 from the segment 46.

The friction existing between the driving strip 35 and the friction pulleys 34 is such that slippage can occur whenever the handle 40 is turned. As soon as the handle 40 is released, the spring 45 will extend itself and return the gear 44 into

engagement with the segment 46, again locking the window and disengaging the pinion 69 and handle 40.

Accordingly it will be seen that, by the present invention, I have provided a novel and improved window operating mechanism whereby the window may be raised by power by energizing the motor 24, or may be raised manually by turning the handle 40, such mechanism being so arranged that during power operation of the window the handle 40 will not turn, yet manual operation may be effected by the mere act of turning the handle without first resetting or converting the mechanism for manual operation. In addition, I have provided means automatically locking the windowpane in any adjusted position whenever it is not being actuated either manually or by power. The mechanism I have provided is simple and economical in construction, relatively small and compact, and is reliable in operation at all times.

In addition to independent actuation of the windowpane 10 by either the power means or the manual means, it should be noted that both of these may be simultaneously employed if desired. Thus if a window should become stuck for some reason, as for example, if it is frozen to the frame because of sleet, ice, etc., both the handle 40 and the motor 24 may be employed to shift the window.

A modification of the invention is shown in Figs. 8 and 9. In this modification, automatic locking of the windowpane 10 is effected by means directly engageable with the gear segment 46. As shown, a bracket 77 is mounted on the upright 17 and carries the unlocking solenoid 51 and plunger 50. The plunger 50 is connected to a lever 78 mounted on the bracket 77, having an arm 79 engageable with the teeth of the gear segment 46. The lever 78 has a second arm 80 engageable with a flange 81 carried by the pinion 69. Whenever the solenoid 51 is energized, as shown in Fig. 9, it will disengage the arm 79 from the gear segment 46, releasing the gear segment and the windowpane 10 for movement. De-energizing of the solenoid will result in the arm 79 again engaging the segment 46 to lock the window. If the window is to be operated manually, turning of the handle 40 and shifting of the pinion 69 to the right as viewed in Fig. 9 will cause the flange 81 thereof to engage and move the lever arm 80, thereby disengaging the lever arm 79 from the gear segment 46 to unlock the latter prior to the pinion 69 meshing with said segment. Upon removal of force from the handle 40 the spring 45 will return the pinion 69 to the left, out of engagement with the gear segment 46.

Variations and modifications may be made within the scope of the claims and portions of the improvements may be used without others.

I claim:

1. The combination of a windowpane; means for mounting the windowpane on a support for movement between open and closed positions; power means connected with said mounting means and windowpane, for opening and closing the latter; a manually-operable member turnable with respect to said mounting means; and means including a clutch for opening and closing the windowpane in response to solely turning movement of said member, said clutch being normally disengaged when turning force is removed from the manually-operable member to enable the windowpane to be actuated by said power

means without causing movement of said member.

2. The combination of a windowpane; means for mounting the windowpane on a support for movement between open and closed positions; means connected with said mounting means and windowpane and including a power unit, for actuating the windowpane, said means further including a friction drive which slips when overloaded, said drive enabling the windowpane to be moved while the power unit is at a standstill; a manually-operable member turnable with respect to said mounting means; and means for actuating the windowpane solely in response to turning movement of said member, said means being normally inoperative when turning force is removed from the manually-operable member and enabling the windowpane to be actuated by said power means without causing movement of said member.

3. The combination of a windowpane; means for mounting the windowpane on a support for movement between open and closed positions; means connected with said mounting means and windowpane and including a power unit, for opening and closing the windowpane, said means further including a friction drive which slips when overloaded, said drive enabling the windowpane to be moved while the power unit is at a standstill; a manually-operable member turnable with respect to said mounting means; and means for opening and closing the windowpane in response to solely turning movement of said member, said means including gears normally out of mesh when turning force is removed from the manually-operable member to enable the windowpane to be actuated by said power means without causing movement of said member, and including a cam mechanism between the member and one of said gears, operable to advance the gear into mesh whenever the member is turned.

4. The combination of a windowpane; means for mounting the windowpane on a support for movement between open and closed positions; means including a power unit, connected with said mounting means and windowpane for actuating the latter, said means further including a friction drive which slips when overloaded, said drive enabling the windowpane to be moved while the power unit is at a standstill; a manually-operable member turnable with respect to said mounting means; and means for actuating the windowpane in response to turning of said member, said latter actuation being accompanied by slippage of said friction drive.

5. The combination of a windowpane; means for mounting the windowpane on a support for movement between open and closed positions; means including a power unit, connected with said mounting means and windowpane for actuating the latter, said means further including an impositive friction drive mechanism enabling the windowpane to be moved while the power unit is at a standstill when slippage occurs in said mechanism; a manually-operable member turnable with respect to said mounting means; and means for actuating the windowpane in response to turning of said member, said latter actuation being accompanied by slippage of said friction drive.

6. The combination of a windowpane; means for mounting the windowpane on a support for movement between open and closed positions; means including a power unit, connected with

said mounting means and windowpane for actuating the latter, said means further including a slip drive comprising a push-pull strip and a pair of juxtaposed power-driven friction wheels engaging opposite sides of said strip to enable the windowpane to be moved while the power unit is at a standstill; a manually-operable member turnable with respect to said mounting means; and means for actuating the windowpane in response to turning of said member, said latter actuation being accompanied by slippage of said strip on said friction wheels.

7. The combination of a windowpane; means for mounting the windowpane on a support for movement between open and closed positions; means connected with said mounting means and windowpane and including a power unit, for opening and closing the windowpane; said means further including a friction drive which slips when overloaded, said drive enabling the windowpane to be moved while the power unit is at a standstill; a manually-operable member turnable with respect to said mounting means; means for opening and closing the windowpane in response to solely turning movement of said member, said means including gears normally out of mesh when turning force is removed from the manually operable member to enable the windowpane to be actuated by said power means without causing movement of said member, and including a cam mechanism between the member and one of said gears, operable to advance the gear into mesh whenever the member is turned; means normally locking the windowpane against movement; and means rendering said locking means inoperative in response to advance of said one gear into mesh.

8. The combination of a windowpane; means for mounting the windowpane on a support for movement between open and closed positions; means connected with said mounting means and windowpane and including a power unit, for opening and closing the windowpane, said means further including a friction drive which slips when overloaded, said drive enabling the windowpane to be moved while the power unit is at a standstill; a manually-operable member turnable with respect to said mounting means; means for opening and closing the windowpane in response to solely turning movement of said member, said means including gears normally out of mesh when turning force is removed from the manually operable member to enable the windowpane to be actuated by said power means without causing movement of said member, and including a cam mechanism between the member and one of said gears, operable to advance the gear into mesh whenever the member is turned; means normally locking the windowpane against movement; means rendering said locking means inoperative in response to advance of said one gear into mesh; and means rendering said locking means inoperative when the power unit is operative.

9. The combination of a windowpane; means for mounting the windowpane on a support for movement between open and closed positions; means including a power unit, connected with said mounting means and windowpane for actuating the latter, said means further including a friction drive which slips when overloaded, said drive enabling the windowpane to be moved while the power unit is at a standstill; a manually-operable member turnable with respect to said mounting means; means for actuating the win-

dowpane in response to turning of said member, said latter actuation being accompanied by slippage of said friction drive; means normally locking the windowpane against movement; means rendering said locking means inoperative when the power unit is operative; and means rendering said locking means inoperative in response to initial turning movement of the manually-operable member.

10. The combination of a windowpane; means for mounting the windowpane on a support for movement between open and closed positions; means connected with said mounting means and windowpane and including a power unit, for actuating the windowpane, said means further including a friction drive which slips when overloaded, said drive enabling the windowpane to be moved while the power unit is at a standstill; a manually-operable member turnable with respect to said mounting means; means for actuating the windowpane in response to solely turning movement of said member, said means being normally inoperative when turning force is removed from the manually-operable member and enabling the windowpane to be actuated by said power means without causing movement of said member; means normally locking the windowpane against movement; and means rendering said locking means inoperative in response to initial turning movement of said member.

11. The combination of a windowpane; means for mounting the windowpane on a support for movement between open and closed positions; means connected with said mounting means and windowpane and including a power unit, for actuating the windowpane, said means further including a friction drive which slips when overloaded, said drive enabling the windowpane to be moved while the power unit is at a standstill; a manually-operable member turnable with respect to said mounting means; means for actuating the windowpane in response to solely turning movement of said member, said means being normally inoperative when turning force is removed from the manually-operable member and enabling the windowpane to be actuated by said power means without causing movement of said member; means normally locking the windowpane against movement; and means rendering said locking means inoperative in response to initial turning movement of said member; and means rendering said locking means inoperative when the power unit is operative.

12. The combination of a windowpane; means for mounting the windowpane on a support for movement between open and closed positions; power means connected with said mounting means and windowpane, for actuating the latter; a manually-operable member turnable with respect to said mounting means; means for actuating the windowpane in response to solely turning movement of said member, said means being normally inoperative when turning force is removed from the manually-operable member and enabling the windowpane to be actuated by said power means without causing movement of said member; means normally locking the windowpane against movement; and means rendering said locking means inoperative in response to initial turning movement of said member.

13. The combination of a windowpane; means for mounting the windowpane on a support for movement between open and closed positions; power means connected with said mounting means and windowpane, for actuating the latter;

a manually-operable member turnable with respect to said mounting means; means for actuating the windowpane in response to solely turning movement of said member, said means being normally inoperative when turning force is removed from the manually-operable member and enabling the windowpane to be actuated by said power means without causing movement of said member; means normally locking the windowpane against movement; means rendering said locking means inoperative in response to initial turning movement of said member; and means rendering said locking means inoperative when the power means is operative.

14. The combination of a windowpane; means for mounting the windowpane on a support for movement between open and closed positions; power means connected with said mounting means and windowpane, for actuating the latter; a manually-operable member turnable with respect to said mounting means; means including gears arranged to mesh with each other when the member is turned, for actuating the windowpane

- in response to turning movement of said member, said gears being normally out of mesh when turning force is removed from the manually-operable member to enable the windowpane to be actuated by said power means without causing movement of said member; means including a locking gear meshing with one of said first-mentioned gears, normally locking the windowpane against movement; and means for shifting said locking gear out of mesh when the first-mentioned gears are brought into mesh, thereby rendering said locking means inoperative in response to initial turning movement of said member.

HERBERT G. LEHMANN.
